UNITED STATES PATENT OFFICE.

ISRAEL L. LANDIS, OF LANCASTER, PENNSYLVANIA.

PAVEMENT-CURB.

SPECIFICATION forming part of Letters Patent No. 431,898, dated July 8, 1890.

Application filed November 6, 1889. Serial No. 329,401. (No model.)

To all whom it may concern:

Be it known that I, ISRAEL L. LANDIS, a citizen of the United States, residing at Lancaster, in the county of Lancaster and State of Pennsylvania, have invented certain new and useful Improvements in Pavement-Curbs, of which the following is a specification, reference being had therein to the accompanying drawings, in which—

10 Figure 1 represents a transverse sectional view of a portion of a sidewalk and the adjacent gutter, showing one form of my improved curbing; Fig. 2, a similar view showing another form of my improved metallic curb; Fig. 3, a perspective view of another form of curbing attached to its adjacent block; Fig. 4, a plan view showing the method of setting the curbs and their blocks; and Figs. 5, 6, and 7, views of slight modifications 20 of the invention, which will be hereinafter described.

The design of the present invention is to provide an extremely cheap and durable metallic curbing for pavements constructed of 25 artificial-stone blocks, concrete, asphalt, cement, or other composition usually formed into blocks while in a plastic state; and it consists in certain novel features, which will be fully hereinafter pointed out and claimed.

30 In the drawings, *a* designates the concrete, cement, artificial stone, or other composition blocks which border the outer edge of the pavement, and to which are secured the vertical curb-plates *b*. These plates are any 35 suitable thickness and width, their lower edges extending into the earth a suitable distance to assist in anchoring them. The curb-plates are attached to the outer edges of the stones by means of horizontal bolts *b'*, which 40 extend back into and are embedded in the body of the adjoining stone, the heads of these bolts being countersunk into the face of the curb and their rear ends being provided with projections *b''*, to prevent their 45 withdrawal. To prevent the curb-plates settling too much, they may be provided with foot-pieces *b'''*, as shown in Fig. 1.

As shown in Figs. 2 and 7, I may provide the upper edges of the plates *b* with horizontal 50 inwardly-turned flanges *c*, which may be embedded in the blocks to bring them flush with the sidewalk. Angle-irons *d*, as shown in the same figures, may, if desired, be bolted

to the curb-plates to assist in supporting the pavement-block *a*. 55

In addition to or in lieu of the above means for securing the face or curb plates to their adjoining blocks, I may bend the ends of the plates inwardly and embed them in the sides of the blocks, as shown in Figs. 3, 4, 5, and 6. 60

In setting these curbs I preferably employ the means shown in Fig. 4—that is to say, I take a beam or straight-edge *f* and hold the curb-plates in perfect alignment with each other while the composition is being filled and packed in back of the plates, the straight-edge being allowed to remain in position until the blocks harden and set. It is evident that one curb-plate may be employed for each block, as shown in Figs. 3 and 4, or long 65 curbs employed, to which may be attached any number of blocks as the exigencies of the case may require. The heads of the rods *b'* may be screwed into the plates *b*, or they may be riveted thereto and their struck-up heads 70 countersunk. 75

To keep the blocks *a* and curbs *b* in alignment and "break" the joints between the blocks, the plates *b* may be provided with overlapping extensions *e'*, as shown in Fig. 5. 80

Instead of the rods *b'*, I may employ an angle-iron *a''*, as shown in Fig. 7, and bolt or rivet the same to the inner side of the curb.

The inner ends of the rods *b'* may be bent into a hook and hooked over rods *a'* embedded in the blocks, as shown in Fig. 6, if desired, without departing from the invention. 85

Having thus fully described my invention, what I claim is— 90

The combination, with a composition block *a*, of a metallic curb-plate *b*, having a flange *c* and secured on the face of the said block and extending down into the earth below the same, a rod secured to the curb-plate and entering the composition block, and an angle-iron *d*, secured to the back of the said curb-plate and adapted to support the said block, substantially as herein described. 95

In testimony whereof I affix my signature in presence of two witnesses. 100

ISRAEL L. LANDIS.
